UNITED STATES PATENT OFFICE.

WILLIAM WALLACE KEMP AND WILLIAM H. VAN HORN, OF BALTIMORE, MARYLAND.

METHOD OF AND APPARATUS FOR PRODUCING BLASTS OF HEATED AIR.

1,311,235.

Specification of Letters Patent. Patented July 29, 1919.

Application filed June 23, 1916. Serial No. 105,525.

To all whom it may concern:

Be it known that we, WILLIAM W. KEMP and WILLIAM H. VAN HORN, citizens of the United States, residing at Baltimore, in the 5 county of Baltimore City and State of Maryland, have invented new and useful Improvements in Methods of and Apparatus for Producing Blasts of Heated Air, of which the following is a specification.

10 This invention relates to a method of and apparatus for heating, and has as one of its objects to produce a blast of heated air which is discharged from the heating device under a relatively high pressure, and by 15 means of which a high degree of heat may be obtained.

A further object of the invention is to produce a hot air blast without employing a blower or compressor for forcing the air 20 to be heated through the apparatus, and with which a wide range of temperatures, varying from a relatively low degree to a relatively high degree, may be obtained, and which, therefore, is adaptable of a great variety 25 of uses. Our improved heater may be used to heat a large volume of air, and the temperature to which the air is heated is always under perfect control, and these features make the device particularly adaptable 30 for use in apparatus where drying operations are carried out, but, of course, it may be employed for heating purposes generally.

The above and other objects of our invention are obtained by the structure described 35 in the following specification and illustrated in the accompanying drawings, and wherein:

Figure 1 is a longitudinal section through one form of our improved blast heater.

Fig. 2 is a view similar to Fig. 1 but showing a modification of our device.

Fig. 3 is a longitudinal section through another embodiment of this invention.

Referring to the drawings, wherein like numerals represent like parts in the several views, 10 designates the burner or burner tip which may be of any suitable or improved construction, and to which is connected a supply pipe 11 leading from a suitable source of supply (not shown) of fluid fuel 45 which is preferably maintained under a high pressure.

The supply pipe 11 leading from the source of fuel to the burner is provided with a cock 12, the internal construction of which 55 is not disclosed, as it forms no part of our invention. The cock is provided with a

handle 13 which may be turned to open or close the pipe and regulate the flow of fuel therethrough, and, in the present instance, the cock is disclosed as having a plate 14 60 provided with a suitable scale thereon, and a handle with a pointer 15 moving over the scale to designate the position of the cock.

The burner 10 extends a slight distance into one end of an open-ended tube 16 which 65 may be of any suitable proportions depending upon the pressure with which the fuel is discharged from the burner and other conditions. Upon ignition of the gases issuing from the burner, atmospheric air is 70 entrained at the burner end of the tube 16 and the heated air issuing from the outer end of the tube 16 may be discharged directly into the machine, apparatus, or room to be heated, or it may be distributed by 75 any suitable means to the place where it is to be used for drying or heating.

In Fig. 2, we have shown the structure illustrated in Fig. 1 as having a second tube 17 into which the outer end of the first tube 80 16 projects to a slight distance, and, in this instance, in addition to the air entrained by the first tube, air is drawn into the second tube about the outlet end of the first tube.

In Fig. 3, means for controlling the 85 amount of air entrained into the opening between the adjacent ends of the tubes 16 and 17 is provided, and while this means may be varied in construction, we have shown, in the present embodiment, the tube 90 17 as having a tapering skirt 18 provided with suitable ports 19, and about the skirt 18 is a damper comprising a conical-shaped sleeve 20, having suitable ports which are adapted to be brought into registry with the 95 ports 19. The temperature and volume of the heated air issuing from the outer end of the larger tube 17 may be regulated or controlled either by operating the damper to vary the amount of air entrained by the 100 larger tube, or by turning the cock 12 to admit more or less fuel to the burner. If a lower temperature and a greater volume of air are desired, the damper 20 is turned to bring the ports in the damper and skirt 18 105 into registry, thus permitting a larger amount of air to be entrained by the outer tube, and if a higher temperature and less volume is desired, the damper is turned to close the ports 19 and thus prevent the larger 110 tube from entraining air.

When it is desired to place the device in

operation, the handle 13 is turned to the proper extent to admit the flow of fuel through the pipe 11 to the burner 10. The fuel issuing from the burner is ignited and as the fuel is under pressure, a flame is shot into the tube 16, as is shown in Fig. 1. The heated products of combustion expand and are forced to the outer end of the tube by the relatively high pressure with which the incoming fuel is forced through the burner, and this causes a suction action at the burner end of tube 16, which draws or entrains atmospheric air into the tube about the burner, as designated by the arrows. The fuel upon ignition, and the air upon being heated greatly expand, and this action together with the force with which the fuel is injected into the tube 16 forces the air with considerable velocity from the tube, and, at the same time, air is entrained or sucked into the tube at the burner end by the rarefaction thus created. Thus atmospheric air is drawn into the tube at one end, becomes thoroughly mixed with the products of combustion, and is heated thereby, and the heated air and products of combustion are discharged from the other end of the tube in a highly heated condition and under considerable pressure.

The tube 16 may be placed in any position, and where desirable it may be inclined downwardly from its burner end, the pressure of the fuel together with the expansion of the heated air and products of combustion being sufficient to force the heated air through the tube and overcome any upward draft. We have found that although the tube is inclined downwardly and is nine or ten feet in length, a blast of hot air can be discharged from the lower end of the tube at a temperature of 900 to 1000° F. and at considerable velocity.

Any suitable fuel may be supplied to the burner so long as such fuel is under high pressure, and natural or artificial gas or the like may be used, but we have found that admirable results may be obtained by supplying an explosive mixture to the burner, and while any suitable type of air and gas mixing device may be employed for this purpose, we refer to the apparatus shown and described in the patent to W. H. Van Horn and W. W. Kemp, No. 1,141,466, granted June 1, 1915. In this apparatus, the air and gas are mixed in proper proportions, so that the mixture is self-sustaining; that is, the mixture contains sufficient oxygen for complete combustion of the gas, and thus no outside supporter of combustion is necessary. Where a mixing device such as described in said patent is connected to the pipe 11 to supply a self-sustaining mixture under pressure to the burner, the chemical characteristics of the entrained atmospheric air are in no way modified in passing

through the heater, the air being merely drawn into the tube, heated by the flame of the burner, mixed with the products of combustion, and propelled through and from the tube with considerable velocity due to the force with which the explosive mixture is injected into the tube. By using a self-sustaining mixture such as described, we have found that an intense heat may be obtained, and that the device is very economical in the consumption of fuel, the explosive mixture being completely consumed, and no residue of solid products of combustion remaining. All obnoxious odors are eliminated and the temperature of the air to be heated is always under perfect control.

This invention is susceptible of various other modifications and changes which would be within the spirit of the invention, without departing from the scope of the following claims.

What is claimed is:—

1. In an apparatus for producing a blast of heated air, the combination of a conduit, a burner projecting into one end of the conduit and separated from the side walls thereof by an annular air space, and means for supplying a completely combustible mixture under pressure to the burner, the parts being so related that the flame or burning gases from the burner will be confined entirely within the conduit and that the ignited mixture discharged from the burner under pressure will entrain a body of air supplemental to the combustible mixture through the space surrounding the burner and force it with the non-flaming products of combustion from the other end of the conduit with considerable velocity.

2. In an apparatus for producing a blast of heated air, the combination of a conduit, a burner projecting into one end of the conduit and separated from the side walls thereof by an annular air space, means for supplying a completely combustible mixture under pressure to the burner, and a second conduit of greater diameter than and surrounding and extending forward from the burner containing conduit and open at both ends, the burner containing conduit being of such length that burning gas from the burner will not be projected beyond the end thereof, whereby the products of combustion will be mixed with a supplemental body of air drawn through the rear ends of both tubes, and chemical characteristics of which will not be modified in the tubes, and discharged with considerable velocity.

3. The method of heating herein described which consists in admixing a combustible gas and a supporter of combustion in such quantities that the amount of the latter present will support complete combustion of the gas, discharging the premixed

self-sustaining mixture under pressure into an open ended tube, igniting said mixture and entraining air into the tube without causing combustion of said entrained air, 5 and which entrained air is mixed with the hot products of combustion from the flame and forced through and from the tube with considerable velocity.

4. The method of heating herein described which consists in admixing air and 10 gas in such quantities that sufficient air is present to support complete combustion of the gas, discharging the premixed self-sustaining mixture under pressure into an 15 open ended tube, igniting said mixture, en-

training air into the tube which entrained air is mixed with the hot products of combustion from the flame without being burned and forced through and from the tube with considerable velocity, and also entraining air at the outlet end of the first tube into a second tube. 20

In testimony whereof we have hereunto set our hands in presence of two subscribing witnesses.
